US0D1040604S

(12) **United States Design Patent** (10) **Patent No.:** **US D1,040,604 S**
(45) **Date of Patent:** **** Sep. 3, 2024**

(54) **FOOD PROCESSOR**

(71) Applicant: **BEIJING XIAOMI MOBILE SOFTWARE CO., LTD.**, Beijing (CN)
(72) Inventors: **Tao Wang**, Beijing (CN); **Bo Xu**, Beijing (CN); **Ningning Li**, Beijing (CN); **Baowen Zhao**, Beijing (CN)

(73) Assignee: **BEIJING XIAOMI MOBILE SOFTWARE CO., LTD.**, Beijing (CN)

(**) Term: **15 Years**

(21) Appl. No.: **35/517,210**

(22) Filed: **May 18, 2022**

(80) **Hague Agreement Data**

Int. Filing Date: **May 18, 2022**
Int. Reg. No.: **DM/222225**
Int. Reg. Date: **May 18, 2022**
Int. Reg. Pub. Date: **May 19, 2023**

(30) **Foreign Application Priority Data**
